UNITED STATES PATENT OFFICE.

CORBON L. HARVEY, OF DETROIT, MICHIGAN.

LEDGER BOOK.

Application filed January 3, 1925. Serial No. 435.

My invention relates to loose leaf binders of the type shown and described in United States Letters Patent No. 1,504,040, issued to C. L. Harvey August 5, 1924, and consists in improvements in the back frame.

One object of my invention is to provide an improved back frame construction in which the binding post engaging strips are held in engaged position.

10 Another object is to provide this locking means in such a manner that it will automatically hold the parts upon engagement of the binding posts by the strips.

15 A further object is to provide for the parts a locking means that may be disengaged without the use of a special tool or instrument and without any extra effort on the part of the operator.

20 In the accompanying drawings illustrating my invention,

Figure 1 is an elevation with a side of the upper frame bar removed to show the mechanism therein.

25 Figure 2 is a top view of the upper frame bar with the top wall removed.

Figure 3 is in part an elevation and in part a section taken on line 3—3 of Figure 2.

30 Figure 4 is a cross section taken on line 4—4 of Figure 3.

The numeral 1 in the drawings indicates the base or back member of my improved loose leaf ledger book. 2 are expandible binding posts which are preferably threaded into base 1. Binding posts 2 are provided with annular grooves 3 near their upper extremities. The upper frame bar 4 to which the top cover (not shown) is hingedly connected is preferably formed of two channel-shaped stampings of sheet metal 5 and 6 which enclose slotted lugs 7 and 8 at their ends and are secured together by rivets 9 or by spot-welding to each other and to the lugs. This construction forms a hollow bar 40 of rectangular cross section which possesses a high degree of rigidity for the weight and cost of material and provides space for the post engaging mechanism.

Two strips 10 and 11, preferably stampings, are slidably mounted in bar 4. The inner end of each of said strips is partially cut away and the remaining corner is pivotally connected to a disk 12. Disk 12 is rotatably mounted on rivet or pin 9. The 55 point of connection between strip 10 and disk 12 is diametrically opposite the con-

nnection between strip 11 and disk 12 and the strips 10 and 11 extend in opposite directions from the disk.

60 The posts 2 extend into bar 4 through openings in the underside thereof and through the slotted portions of lugs 7 and 8. Strips 10 and 11 are slotted at 13 and 14 in their outward ends. The slotted portions are 65 adapted to fit into annular grooves 3 on the binding posts and thus connect the bar 4 with the remainder of the ledger book.

A flat spring member 15 has one of its ends riveted to strip 10. This spring is so 70 tensioned that its tendency is to bend away from the strip to which it is fastened except at its free extremity 15^a where it is bent slightly in a reverse direction or back toward the strip.

75 The channel-shaped stamping 5 is provided with a depressed portion 16 over the free end of spring 15. Disposed longitudinally of said depressed portion and of said channel-shaped stamping is a slot 17. A tip or projection 18 is formed preferably on one side of slot 17 by making two short parallel cuts in the edge of said slot and bending the portion between the cuts downwardly or in such direction that the tip will 80 project to the interior of the hollow bar 4.

85 Opening 19 in spring 15 is so located that when strips 10 and 11 are extended as hereinafter explained, the projection 18 will enter this opening and latch the various parts 90 in position.

A button 20 is riveted to spring member 15. The neck of said button extends through slot 17 so that its head 21, which is of slightly greater diameter than the width of the 95 slot, is disposed exteriorly of bar 4 in depressed portion 16.

100 To use my improved ledger book, the operator adjusts the expandible binding posts 2 to suit the height of the number of leaves in use. The button 20 is pushed to the inner limit of its movement and bar 4 with the front cover hingedly attached thereto is placed over the ends of the binding post. Button 20 is then pushed to the outward limit of its movement. The outward movement of button 20 carries with it spring 15 to which the button is riveted. The spring in turn moves strip 10, the slot 13 of which engages in annular groove 3 of the binding 110 post. Strip 11 is moved in a direction opposite to that of its companion piece 10 by means of the connections through disk 12.

The slot 14 in this piece engages with the annular groove 3 of its binding post. As button 20 nears the end of its outward or post engaging movement, the downwardly bent end 15^a of spring 15 strikes against the projection 18 and the spring is depressed sufficiently to permit its passing under the projection. The coincidence of opening 19 in the spring member with projection 18 permits spring 15 to return to its normal position, that is, bearing against the underside of depressed portion 16. This return causes an engagement between a fixed member, the projection, and a movable member, the spring, and firmly holds the post engaging mechanism in engaged position.

The natural and only practical way of moving the button 20 is for the operator to push it with his finger since the head of the button lies in its groove below the normal surface of channel member 5. An almost imperceptible amount of downward pressure is required to depress spring 15 sufficiently to disengage projection 18 from opening 19 to allow the button 20 to be moved to disengage the strips from their respective binding posts. The necessary downward pressure is unconsciously provided by the operator in exerting sufficient effort to move the button in its slot.

In my improved ledger book as described there is no necessity of using a key or any tool to operate the device. No excess friction is required on any of the moving parts since they are positively held in engaged position. Another advantage is that the bar 4 of my device forms a substantially dust-proof case for the operating mechanism. This is provided by the fact that spring 15 closes slot 17 when the strips engage the binding post and the binding posts fill the only other openings.

I claim:

1. In a loose leaf binder, a frame including a binding post and a hollow bar having a slot in one of the walls thereof, a post engaging strip slidably mounted in said bar, a flat spring member one end of which is fastened to said strip and the body of which is bent away from said strip at an angle except the extreme free end of which is slightly rebent, an operating button on said spring

member, said button extending exteriorly of said bar through said slot, a projection in said bar, and means on said spring member for engaging said projection to lock the parts against further movement upon engagement of said binding post by said strip. 55

2. In a loose leaf binder, a frame including a binding post and a hollow bar having a slot in one of the walls thereof, a post engaging strip slidably mounted in said bar, a spring member one end of which is fastened to said strip, an operating button on said spring member, said button extending exteriorly of said bar through said slot, a projection on said bar, and means on said spring member for engaging said projection to lock the parts against further movement upon engagement of said binding post by said strip. 60

3. In a loose leaf binder, a frame including binding posts and a hollow bar, a pivotally mounted disc in said hollow bar, post engaging strips connected to opposite sides of said disc and adapted to move in opposite directions into post engaged and disengaged positions, a spring member having one end fastened to one of said strips, an actuating button on said spring member projecting exteriorly of said hollow bar, and means on said spring member and said hollow bar adapted for engagement to retain said mechanism in post engaged position. 75

4. In a loose leaf binder, a frame including binding posts, a hollow bar having a slot therein and an inwardly extending projection adjacent to said slot, a disc pivotally mounted within said hollow bar, post engaging strips having post engaged and disengaged positions, said strips being pivotally mounted on opposite sides of said disk to move in opposite directions, and an actuating member connected to one of said strips and extending through said slot, said member being yieldable transversely to the longitudinal axes of said strips and rigid relative to its longitudinal position therewith, and means on said member adapted to engage said projection when said strips are in post engaged position. 80

In testimony whereof I hereunto affix my signature this 16th day of December, 1924.

CORBON L. HARVEY.
